UNITED STATES PATENT OFFICE.

ANTONIN R. KOLAR, OF CLINTON, IOWA, ASSIGNOR OF ONE-THIRD TO
KATHERINE A. WILLS, OF SAME PLACE.

COMBINATION-KNIFE.

SPECIFICATION forming part of Letters Patent No. 589,392, dated August 31, 1897.

Application filed August 26, 1896. Serial No. 604,048. (No model.)

To all whom it may concern:

Be it known that I, ANTONIN R. KOLAR, a citizen of the United States, residing at Clinton, in the county of Clinton and State of Iowa, have invented certain new and useful Improvements in Combination-Knives; and I do hereby declare the following to be a full, clear, and exact description of the invention, such as will enable others skilled in the art to 50 which it appertains to make and use the same.

This invention relates to improvements in combination-tools, and has more particular relation to tools that are commonly known as "combination-knives."

15 The invention consists of the combination, with a knife-frame carrying a knife-blade and formed with a wire-cutting end, of another frame carrying a corkscrew and pencil-sharpener and formed into the other member of the 20 wire-cutter, said wire-cutting portions being pivoted together, so that the frames form operating-handles.

The invention also consists of certain other novel constructions, combinations, and arrangements of parts, all of which will be 25 more particularly hereinafter set forth and claimed.

In the accompanying drawings, forming a part of this specification, Figure 1 represents 30 a side elevation of a knife embodying my invention in its closed position. Fig. 2 represents a side elevation of said knife in its open position, and Fig. 3 represents a similar vertical section through my said improved combination-knife.

35 A in the drawings represents the blade-carrying frame, and B the corkscrew and pencil-sharpener carrying-frame. The frame A is provided with a pivoted knife-blade a and is 40 formed at its forward end into a disk a', having a cutting-jaw a² and a wire-nipping recess a³. The frame B is also provided at its forward end with a disk b, having a cutting-jaw b', said disk b being pivoted to the disk 45 a' by means of a pivot-pin b². The said frames A and B are held normally separated to hold the jaws a² and b' open by a spring b³, applied upon a pin b⁴ on frame B and having its opposite ends extending into contact with said 50 frames A and B, respectively.

It will be observed from the above that when the frames A and B are brought together by the pressure of the hand the jaws a² and b' are closed and cut any substance that is between them. It will also be observed that 55 if a piece of wire be inserted into the recess a³ the closing of the jaw b' past said recess will cut the wire therein.

A corkscrew b⁵ is pivoted within a suitable recess in the frame B by a pin b⁶. The inner squared end of said corkscrew b⁵ engages a flat spring b⁷, mounted on said frame, and thus causes said corkscrew to spring into either an open or closed position and remain so under spring tension. The said spring b⁷ 65 also projects forward past the end of the corkscrew and engages an angular pivot-pin b⁸, mounted in the frame B and provided with a latching-arm b⁹ and operating-handle b¹⁰.

Suitable latch-eyes b¹¹ and b¹² are provided 70 upon the respective frames A and B, so that when said frames are brought together said eyes will coincide in position, and upon the rotation of the pin b⁸ the latch-arm b⁹ will pass through said eyes and thus hold the two 75 frames firmly together against the tension of the spring b⁷. This rotation of the pin b⁸ is caused by the handle b¹⁰. The said pin b⁸ will be held in any of its adjusted positions 80 by means of the end of the spring b⁷ pressing against its angular sides. Suitable thumbnotches a⁵ and a⁶ are provided in the respective frames A and B, so that the finger-nail may be readily inserted to raise either the cutting-blade a or the corkscrew b⁵ into operative position. The outer end of the frame B is provided with a conical pencil-sharpening recess b¹³, in the wall of which is set an inclined sharpening-blade b¹⁴ by means of screws b¹⁵.

90 It will be observed from the foregoing description that I provide in one implement a knife, a cutter, wire-nippers, a corkscrew, and a pencil-sharpener, the whole being adapted to be closed into a compact form, so 95 that the knife may be stored away in a vest pocket if so desired. It will also be observed that when so desired the blade b¹⁶ of the pencil-sharpener may be removed for sharpening or repairs.

Having now described my invention, what I claim as new, and desire to secure by Letters Patent, is—

1. In a combination-tool, the combination 5 with a frame carrying a knife-blade and one jaw of a cutter, of another frame carrying a corkscrew, a pencil-sharpener and the other jaw of a cutter, a pivot-pin connecting said frames, a spring for holding said frames nor- 10 mally separated, a spring for holding the corkscrew in either its open or closed position, and a catch adapted to lock the two frames together and engaged by said latter spring to hold it in its adjusted position, sub- 15 stantially as described.
2. In a combination-tool, the combination with a frame carrying a knife-blade and a

cutting-jaw, of another frame carrying a cork-screw, pencil-sharpener, and a cutting-jaw, and pivoted to the first-mentioned frame, a 20 spring for keeping said frames normally sep- arated, a spring for holding the corkscrew in either its open or closed position, securing-eyes formed on said frames respectively, and a pivot-catch adapted to pass through said 25 eyes to secure the frames together, substan-tially as described.

In testimony whereof I have signed this specification in the presence of two subscrib-ing witnesses.

ANTONIN R. KOLAR.

Witnesses:

JOHN W. LEMING,
CHARLES DICKINSON.
